(57) CLAIM

The ornamental design for a bead holding case, substantially as shown and described.

DESCRIPTION

FIG. 1 is a front elevational view of the novel bead holding case when its lid is fully opened;

FIG. 2 is a rear elevational view of the novel bead holding case when its lid is fully opened;

FIG. 3 is a left side elevational view of the novel bead holding case when its lid is fully opened;

FIG. 4 is a right side elevational view of the novel bead holding case when its lid is fully opened;

FIG. 5 is a top plan view thereof;

FIG. 6 is a bottom plan view thereof;

FIG. 7 is a front elevational view thereof when the lid is closed;

FIG. 8 is a right side elevational view thereof when the lid is closed; and,

FIG. 9 is a perspective view thereof when the lid is fully opened.

The broken line structure throughout the drawing disclosure is for illustrative purposes only and forms no part of the claimed design.
